Albert Tolten
his Atty.

UNITED STATES PATENT OFFICE.

ROBERT D. PIKE, OF SAN FRANCISCO, CALIFORNIA.

ROASTING FURNACE.

Application filed November 19, 1923. Serial No. 675,447.

To all whom it may concern:

Be it known that I, ROBERT D. PIKE, a citizen of the United States, residing at city and county of San Francisco, and State of California, have invented certain new and useful Improvements in a Roasting Furnace, of which the following is a specification.

The hereinafter described invention relates to cooling means or means for maintaining circulation of air through the rabbling mechanism of multiple hearth mechanical roasting furnaces and more especially, those in which highly endothermic reactions are carried at relatively high temperature. In this class of furnaces the temperature maintained in the lower part is exceedingly high and requires the incorporation within the furnace of more highly efficient cooling means than provided for at the present time and for the accomplishment of the purposes desired the cooling means are required to be of such a form as will combine an efficient cooling of the metal of the rabbling mechanism with a minimum abstraction of heat from the furnace.

The present type of ore roasting furnaces to which this invention is more particularly applicable are provided with a rotating column formed of two concentric members, to the outer one of which the rabble arms are attached. These members of the column are so arranged as to take fresh air for cooling of the rabble arms into the central duct of the rotating column at the bottom thereof, of which air ascending therein passes into and through the rabble arms in parallel, each rabble arm receiving fresh cooled air from the rotating column and each discharging heated air into the annular duct thereof through which it rises and passes out of the top of the column. Under this construction the only air which passes through the annular duct of the central rotating column is air which has been heated by passing through and discharging from the rabble arms, no provision being made for causing a flow of air for the cooling of the outside metal of the centrally disposed rotating column at the lower end portion thereof and which it is essential to protect. The construction of such a form of centrally disposed rotating column utilized in a multiple hearth mechanical roasting furnace is fully set forth and described in my United States

Letters Patent No. 1,466,382, dated August 28th, 1923.

By my present invention means are provided at or adjacent the bottom of the centrally disposed rotating column and substantially at a level with the bottom hearth of the furnace for permitting a by-passing of a regulated quantity of cool air directly from the central duct of the rotating column into the annular duct thereof, said by-passing of the air being controlled by means external to the furnace and which permits of the air passing directly to the annular duct and such of the air as is constrained to pass through the rabbling arms to be regulated at the will of the operator.

For an understanding of the invention, reference should be had to the accompanying sheet of drawings wherein is illustrated a broken vertical sectional view of a multiple hearth roasting furnace with my invention applied thereto. In the drawings the numeral 2 is used to designate a multiple hearth mechanical roasting furnace which is provided with a centrally disposed rotating hollow column, which column supports the hollow rabble arms 3 disposed to work over the several hearths 4 arranged in superposed relation within the furnace. The centrally disposed rotating column comprises the concentrically disposed shells 5 and 6, which form an outer annular duct 5' and an inner duct 6'. Preferably the members of the centrally disposed column are formed of cast-iron and made in a plurality of sections, the inner shell 6 being rigidly held with respect to the outer shell 5 by means of spiders 7 fixed at intervals within the annular duct 5'. This annular duct or space 5' at its bottom is separated from or closed to the outside atmosphere by the partition wall 8, and inner or central duct 6' of said rotating column is closed at its upper end or top by the cover wall or partition plate 9, only allowing for a passage therethrough of a centrally disposed rotatable rod 10. At its upper end the outer annular space 5' of the rotating column communicates with the outside through the medium of slots 11 in communication with an interior chamber 12 of a fixed housing 12', with which housing connects an outlet pipe 13. A bearing 14 supported on structural member 15 supports or upholds the housing 12', which housing

has a central passage in the bottom wall thereof through which is extended the restricted portion 16 of the outer shell 5 of the rotating centrally disposed column. The 5 rotatable rod 10 passes through an aperture formed in the top wall 17 of the housing 12' and held in place by an inwardly disposed collar 18 bearing against the under face of the cover plate 17 and a lock nut 19 applied outside of the cover 17. The lock nut 19 in conjunction with the collar 18 serves to hold the rotatable rod 10 securely in locked position, but when the lock nut 19 is loosened the rod 10 is free to be turned by 10 the handle 20 relative to the central column, which relative position of the rod can then be fixed or secured by a tightening of the lock nut 19. The said rotatable rod 10 is supported with respect to the central duct 20 6' by means of the spiders 21 suitably spaced within the inner shell 6 of the centrally disposed rotating column.

The inner shell 6 terminates at its lowered end extended below the roasting furnace in 25 a bottom pin 22, which seats within a bearing 23 and rotates within a body of oil 24 contained therein, the whole being supported on a suitable foundation 24^a. Air under pressure is admitted from a suitable outside 30 source through the supply pipe 25 into a chamber 26 surrounding the lower portion of the central shell 6 and flows from said chamber 26 within the shell 6 through the inlet openings 27 formed in that portion of the said shell situated within the chamber 26. Rotary motion is transmitted to the centrally disposed column through the medium of the gear 28, which meshes with a pinion 28^a driven from any suitable source of 35 power.

A regulated portion of the cooling air passing upwardly through the inner shell 6 makes its escape from within the central duct 6' into the annular passage 5' through 40 outlet ports 28', suitably situated in the wall of the inner shell 6 and that portion thereof on a level substantially corresponding with the level of the bottom hearth 29 of the furnace. The passage of the air through the 45 outlet ports 28' is regulated or controlled by the position of the slotted cage 30 attached to the rotatable rod 10 at the lower end thereof, the circumferentially disposed slots or ports 30' of which correspond with the outlet ports 28' of the central shell 6. As the rod 10 is rotatable relative to the shell 6, the area of the passage between the inner duct 6' and the annular passage 5' of the centrally disposed 50 rotating column may be varied from the full area of the outlets 28' to zero, dependent entirely upon the positioning of the ports 30' of the cage 30 with respect to said outlets 28'.

Such of the cooling air as does not pass directly from the duct 6' into the annular space

5' of the central column moves upwardly within the duct 6' and escapes therefrom through the spaced ducts 32 of the shell 6 into the hollow rabble arms 3 and after circulating therethrough for a cooling thereof, 70 discharges therefrom into the annular space 5' through the inlet openings 33 formed in the wall of the shell 5 and which communicate with the interior of the hollow rabble arms 3, thence passing upwardly makes its 75 escape from the centrally disposed column through the outlets 11 into the chamber 12 of the housing 12'.

Through the use of the described invention 80 the operator is enabled to divide a given stream of cooling air entering into the apparatus from the air supply conduit 25 into two streams of regulated proportions, one stream passing directly into the annular passage 5' for effectively cooling the metal walls thereof and the other stream flowing upwardly within the shell 6 being utilized for the cooling of the rabble arms, thereby enabling a more efficient cooling of the central 85 rotating column at the bottom thereof and within the zone of maximum heating than is permitted under present construction and at the same time I am enabled to effectively cool the entire central column independently 90 of the cooling of the rabble arms.

While I have illustrated and described the invention in its preferred embodiment, I do not wish to be understood as confining or restricting myself to the details of construction of working parts as illustrated and described but wish to be understood as claiming the invention as broadly as the state of 100 the art will warrant.

Having thus described my invention, what I claim as new and desire to secure by Letters Patent, is:

1. In a multiple hearth furnace, a vertical rotating central column, composed of spaced concentric shells providing an inner air duct and an outer annular air duct, means for introducing air into the lower end of the inner air duct and for escape of air from the upper end of the outer annular air duct of the rotating column, hollow rabble arms secured to and carried by the central column, connections for passing cooling air from the inner air duct of the column into the rabble arms and connections for delivering air from the rabble arms into the annular air duct of said column, and means at the approximate lower level of the furnace for passing cooling air direct from the inner air duct of the rotating column into the outer annular air duct thereof.

2. In combination with a multiple hearth furnace, a centrally disposed rotating column mounted therein and comprising spaced concentric shells providing an inner air duct and an outer annular air duct, means for admitting cooling air into the inner shell of

the column, outlet ports formed in the wall of the inner shell adjacent the lower end thereof, means within said shell for controlling the flow of air through the outlet ports 5 thereof into the annular air duct of the rotating column, and manually operated devices for actuating said means for regulating

the flow of air from the inner air duct into the outer annular air duct of the central column.

In testimony whereof I have signed my name to this specification.

ROBERT D. PIKE.
